UNITED STATES PATENT OFFICE.

WILLIAM F. CONKLIN, OF TARENTUM, PENNSYLVANIA.

CLAMP.

1,390,087.

Specification of Letters Patent. Patented Sept. 6, 1921.

Application filed October 21, 1920. Serial No. 418,508.

To all whom it may concern:

Be it known that I, WILLIAM F. CONKLIN, a citizen of the United States, residing at Tarentum, in the county of Allegheny and 5 State of Pennsylvania, have invented certain new and useful Improvements in Clamps, of which the following is a specification.

My invention consists of an improvement in clamping devices for ropes, cables, etc. 10 It has for its object to provide means for quickly and positively clamping and fixedly holding a flexible cord, rope, cable, or the like, or any insertible flexible element, between the bearing faces of a socket and a 15 relatively adjustable binding wedge member. It operates on the principle of clamping a flexible element of the kind noted by forming a kink or undulation therein, and utilizes either one or more adjustable clamping devices, 20 in combination with the bearing faces of a suitable frame, so arranged as to effect the bending of the element to be held.

In the drawings, I have illustrated various forms of the invention, but it will be readily 25 understood that the invention may be utilized in other shapes or arrangements, or in connection with various forms of holding frames, and in various applications. In certain preferred embodiments of the invention, 30 illustrated in the drawings,

Figure 1 is a view of a clamping apparatus in front elevation, partly broken away;

Fig. 2 is a vertical sectional view on the line II—II of Fig. 1;

Fig. 3 is a sectional detail view on the line III—III of Fig. 1;

Fig. 4 is a view similar to Fig. 1 showing the clamp in operative position at one side, with a flexible element held thereby;

Fig. 5 is a transverse sectional view on the line V—V of Fig. 1;

Fig. 6 is a view in sectional elevation showing a modified construction of the invention;

Fig. 7 is a similar view showing a further 45 modification, utilizing a single adjustable wedging or clamping element, the section being taken on the line VII—VII of Fig. 8; and

Fig. 8 is a vertical sectional view on the 50 line VIII—VIII of Fig. 7.

Referring to the principal figures of the drawings, I provide a main frame or body portion 2 having at its rear side one or more attaching flanges 3 adapted to be secured 55 against a wall or other plane surface by

screws, as shown. At each side of the middle of the frame, are provided wedge shaped receiving sockets 4—4 formed in the frame 2, the central portions of which converge inwardly, providing V-shaped receiving grooves or sockets 5, which in cases where insulation is desired, are faced with liners 6 of suitable insulating material. In such construction, the main frame 2 forms the inner side of the groove and an outer 60 front plate 7 is secured thereon by screws or bolts in the manner shown, and with an inner corresponding sloping wall forming, with the base of the frame, the continuous V-shaped groove 5, as will be readily understood. 65

The inner cavities, as thus formed, provide for the insertion of the clamping or binding wedge members 8 between the frame and plate 7 at each side of the metal, as in 70 alinement with the series of V-shaped grooves which, together with the intervening wedge members 8, form the alternating or tortuous path for the flexible member to be clamped. 75

The outer terminals of the outside grooves and the intervening apex of the middle grooved pathway are rounded, as indicated at 80 9, providing for a curved bend of the flexible member A, as indicated in Fig. 4. 85

The clamping members 8 are provided with binding edge terminals 10 which, as shown in Fig. 3, are the edge portions of insulating material extending across midway of each member and clamped between 90 the front 11 and back 12 thereof by securing screws or bolts 13, as shown. By this construction, I not only provide for complete insulation when desirable, but also for comparatively narrow binding edge projections adapted to engage directly against the flexible member A, as clearly shown in Fig. 4. 95

Each clamping member 8 is provided at its central terminal with a binding groove 100 14 of V-shape in cross section, and in longitudinal alinement with the receiving grooves of the holding base member, adapted to positively engage and depress the flexible member within the socket 4 at one side or the 105 other, when either clamp member is actuated. Each of said members is connected by an attaching wing 15 to a holding bolt 16 by which it is in slotted engagement, as at 17, with the yoke 18. Said yoke is pivoted by 110

stud 19 at its middle to the supporting post 20, which is mounted for vertical adjustment in the frame.

A spanner 21 bears upon the upper edge 5 portion of yoke 18 and is subject to the constant pressure of a spring 22, seated in the member 21 and in an upper receiving terminal 23 of post 20, through which a squared stem 24 of member 21 extends for 10 guidance, and prevention of lateral turning, as clearly shown in Figs. 1 and 2. The object of such construction is to equalize the pressure on yoke 18 when the parts are released, so as to normally hold the yoke and 15 its parts level.

Post 20 is provided with a threaded extension 25 in threaded engagement with a gear 26 having a bearing at each end in the main frame and a bracket 27 thereof respectively, 20 as shown. An intermeshing gear 28 mounted by its stem 29 in a depending bearing 30 of the front plate 7 is provided with an operating crank 31 for raising or lowering post 20 by the gearing shown. Lugs 32 extend 25 outwardly from yoke 18 at each side of wing 15 with sufficient clearance to provide for a limited shifting movement while maintaining the clamping member 8 in approximate operative position.

30 As shown in Fig. 4, the flexible member A is placed through the receiving grooves and passageways between the bearing surfaces of the frame and the clamping members, and, when the clamping members are sufficiently 35 far from the coacting bearing faces of the frame, the flexible member may be drawn without any effort. When the clamping members, however, are sufficiently adjusted, tension on flexible member A in one direction or another will, by binding upon the 40 fork 14 of one of the clamping members, thrust it upwardly at one side, effecting a corresponding downward thrust of the other member, so as to fixedly clamp and positively hold the flexible member against further movement. Likewise, upon reversal of the tension in the opposite direction, the other member will be thrust upwardly and its companion member downwardly, clamping 45 the flexible member in the same manner. The adjustment of the mounting of the pivoted yoke 18 provides for the insertion and gripping action of the cables, etc., of varying diameter, and it will be readily observed 50 that, by the gearing shown, the device is capable of very accurate setting.

In Fig. 6, I show a modified construction in which the clamping members 8^a are pivotally connected by their wings 15^a with 60 the supporting studs 16^a and slotted terminals 17^a to the yoke arm or lever bar 18^a. Said frame is pivoted, as by stud 19^a, to any suitable support, as a post 20^a, extending upwardly from the rear of the main frame 65 2^a, and is also provided with one or more

terminal handles 32^a. Each clamping member 8^a in this construction is provided with terminal grooved rollers 14^a carried by pivoting pins or bolts 14^b, and corresponding rollers 9^a are mounted by pins or bolts 9^b 70 at alternating positions, corresponding to the rounded portions 9, whereby to provide the alternating pathway for the flexible member, as a rope or cable A.

Hollow terminal extensions 33^a extend 75 from one or both ends of the main frame 2^a, as shown, through which the flexible member A is passed. In this construction, the invention is capable of being used in various different ways, as for instance, in lowering a weight by gradually supplying the necessary tension and resulting friction to the cable. Thus, the frame 2 may be provided with a snap hook or other suitable connection so as to be attached to the belt 80 of a person. In such case, assuming one end of the cable A is attached to an upper support, he may use the device to lower himself to the ground, controlling the speed of descent by applying suitable pressure by 85 grasping the hollow terminal 33^a and lever terminal 32^a and pressing them together. Various other utilizations of the invention may be also made by applying it to the particular use in view. 95

In Figs. 7 and 8, I show a further modification in which a single clamping member 8^b is used, of generally similar construction to that already described, having lateral edge projecting portions 10^b and a middle forked 100 terminal 14^b, coacting with a receiving V-shaped recess 4^b of a frame 2^b. In such construction the clamping member 8^b is made integral with or fixedly connected to a post 20^b mounted for vertical adjustment in the frame by means of gears 26^b and 28^b, the latter of which is mounted in bearings 30^b by stem 29^b and is provided with a terminal 31^b for attachment of an operating crank. 105

In such construction, the clamping action is effected by positively adjusting member 8^b within the V-shaped passageway or recess for the flexible member, which is positively clamped therein by adjustment of the clamping member by the gearing to any desired pressure. 110

In either form of the invention, the holding action on the flexible member is effected through the abrupt kink or bending of the cable, rope, or the like, in an undulating passage so as to positively hold it against movement. Thus, the flexible member, if approximately cylindrical, is engaged at two points by the V groove of the frame and at another point midway of these by the binding member, giving a three point contact, a strap or other rectangular member may be grasped and held in the same way. 120

The device may be variously changed or modified in different details of construction, 130

proportions, or designs, to suit various conditions of use by the skilled mechanic, but all such changes are to be considered as within the scope of the following claims.

5. What I claim is:

1. A clamping device for flexible members comprising a body member having a concaved passageway therein through which the flexible member may be passed in a direction longitudinally of the body, and a relatively adjustable clamping member movable transversely of the body adapted to be forced into the concaved passageway to engage the flexible member.
10. 2. A clamping device for flexible members comprising a body member, a V-shaped recess forming a passageway through which a flexible member is adapted to be passed, a relatively adjustable clamping member movable transversely to the passageway and adapted to be forced into the V-shaped recess to engage the flexible member to force it into clamping relation with the sides of the recess.
15. 3. A clamping device for flexible members comprising a body member having a concaved passageway therein through which the flexible member may be passed in a direction longitudinally of the body, a relatively adjustable member movable transversely of the body and adapted to be forced into the concaved passageway to engage the flexible member, and gearing for effecting such transverse movement of the adjustable clamping member.
20. 4. A clamping device for flexible members comprising a body having an undulating passageway therein through which a flexible member may be passed, movable clamping members co-acting with the undulating portions of the body, and means connecting the movable clamping members in such manner that said members may be moved in unison.
25. 5. A clamping device for flexible members comprising a body having an undulating passageway therein through which a flexible member may be passed, movable clamping members co-acting with the undulating portions of the body, and means connecting the movable clamping members in such manner that a tendency of the flexible member to move one member in one direction will force another member in an opposite direction.
30. 6. A clamping device for flexible members comprising a body having an undulating passageway therein through which a flexible member may be passed, movable clamping members co-acting with the undulating portions of the body, and means connecting the movable clamping members in such manner

tions of the body, means connecting the movable clamping members in such manner that movement of one member in one direction will move another member in an opposite direction, and means for moving the movable clamping members out of clamping relation with the flexible member.

65. 7. A clamping device for flexible members comprising a body having an undulating passageway therein through which a flexible member may be passed, movable clamping members co-acting with the undulating portions of the body, a lever pivoted between its ends and having one of said movable clamping members connected thereto at each side of its pivot point.

70. 8. A clamping device for flexible members comprising a body having an undulating passageway therein through which a flexible member may be passed, movable clamping members co-acting with the undulating portions of the body, a lever pivoted between its ends and having one of said movable clamping members connected thereto at each side of its pivot point, and means for moving said lever relatively to the body to move said clamping members into or out of the undulating passageway.

75. 9. A clamping device for flexible members comprising a body having an undulating passageway therein through which a flexible member may be passed, movable clamping members co-acting with the undulating portions of the body, a lever pivoted between its ends and having one of said movable clamping members connected thereto at each side of its pivot, means for moving said lever relatively to the body member to move said clamping members into or out of the undulating passageway, and a spring for normally holding the lever in such position as to maintain the adjustable clamping members in the same position relatively to each other.

80. 10. Clamping mechanism for a flexible member comprising a body having a V-shaped passageway, a relatively adjustable clamping member carried on the body and movable transversely of the passageway and adapted to be forced thereinto, said clamping member being wedge-shaped and being provided with a grooved end portion and edge portions projecting beyond the sides of the wedge-shaped member.

85. In testimony whereof I hereunto affix my signature.

WILLIAM F. CONKLIN.
